Primary Examiner — Kimberly Barnes

(74) Attorney, Agent, or Firm — Cramer Patent & Design, PLLC; Aaron R. Cramer

(57) **CLAIM**

The ornamental design for a pillow, as shown and described.

DESCRIPTION

FIG. 1 is a perspective top front right view of a pillow, showing our new design;

FIG. 2 is a front elevation view, with a rear elevation view being identical thereof;

FIG. 3 is a right elevation view, with a left elevation view being identical thereof;

FIG. 4 is a top plan view thereof; and,

FIG. 5 is a bottom plan view thereof.

The alternating thick and thin diagonal line shading is intended to represent a fastening material such as hook and loop fabric.
